UNITED STATES PATENT OFFICE.

GEORGE S. HILL, OF STRAFFORD, NEW HAMPSHIRE, ASSIGNOR TO UNITED SHOE MACHINERY COMPANY, OF PATERSON, NEW JERSEY, A CORPORATION OF NEW JERSEY.

BUTTONHOLE-SEWING MACHINE.

1,216,316.

Specification of Letters Patent. Patented Feb. 20, 1917.

Application filed February 26, 1915, Serial No. 10,699. Renewed January 11, 1917. Serial No. 141,913.

To all whom it may concern:

Be it known that I, GEORGE S. HILL, a citizen of the United States, residing at Strafford, in the county of Strafford and State of New Hampshire, have invented certain new and useful Improvements in Buttonhole-Sewing Machines; and I do hereby declare the following to be a full, clear, and exact description of the invention, such as will enable others skilled in the art to which it appertains to make and use the same.

The invention relates to buttonhole sewing machines of that class in which a work holding clamp and a stitch forming mechanism are relatively movable to form over-seam stitches extending along the sides and about the ends of a buttonhole.

The object of the invention is to provide novel and improved mechanism for starting the machine, for controlling the driving mechanism during the operation of the machine, and for stopping the machine at the completion of a cycle of operations incident to cutting and sewing a buttonhole. To this end the invention comprises the features of construction and combinations of parts hereinafter described and referred to in the claims.

The invention will be readily understood from an inspection of the accompanying drawings and the following detailed description of the mechanism illustrated therein.

In the drawings, Figure 1 is a side elevation partly in section showing so much of a buttonhole sewing machine as is necessary to illustrate the application of the present invention thereto; Fig. 2 is a detailed side elevation, partly in section, showing the preferred form of the invention; Fig. 3 is a detailed plan view of the feed cam gear and certain of the cams carried thereby; and Fig. 4 is a detailed sectional elevation on line 4-4, Fig. 3.

In the drawings the invention is illustrated as embodied in a buttonhole sewing machine having substantially the construction and mode of operation of the machine shown and described in Patent No. 1,063,880, June 3, 1913. In this machine the stitch forming mechanism comprises an upper needle 2 eccentrically mounted in a vertically reciprocating needle bar 4, an under needle indicated in dotted lines at 6, and a co-operating looper (not shown). The upper

needle bar and the under needle and looper are mounted respectively in a rotary head and in a rotary turret which are rotated during the sewing about the end and eye of a buttonhole. The work is held in a clamp which comprises upper clamp arms 8 pivoted on cooperating clamp plates 10 which are in turn mounted on the clamp carrier 12. The clamp carrier is moved longitudinally to bring the work into register with the buttonhole cutter 14, or into register with the stitch forming mechanism, and to feed the work during the sewing by a cam groove formed in a cam gear 16, which makes one revolution for each cycle of the machine. The clamp carrier is moved laterally, and the stitch forming mechanism is rotated during the sewing through suitable connections from a gear 18 which is mounted concentrically with the gear 16, and which makes one revolution during the sewing of each buttonhole. The cutter 14 is operated from a cam on the gear 16, and when operated to cut a buttonhole, also operates to close the clamp arms 8, which are held closed during the sewing by latching devices mounted on the clamp carrier.

The stitch forming mechanism is driven during the sewing through a clutch mounted on the sewing shaft 20. The sewing clutch is thrown into and out of operation through a vertically movable actuator bar 22, the upper end of which is connected with the clutch shifting devices and the lower end of which is arranged to be operated upon by a cam ledge 24 carried by the cam gear 16.

When the machine is at rest the upper and under needles are in their retracted positions, and the clamp is in position to register with the cutter and is open. When the machine is started, the gear 16 is given a partial revolution at a comparatively high speed to operate the cutter, close the clamp, and move the clamp forward into position to bring the buttonhole slit into register with the sewing mechanism, the gear 18 remaining stationary. The sewing mechanism is then started, and during the sewing the gears 16 and 18 are driven at a comparatively slow speed to feed the clamp and to rotate the stitch forming mechanism. When the sewing of the buttonhole is completed, the operation of the stitch forming mechanism and the rotation of the gear 18 is

stopped, while the rotation of the cam carrying gear 16 is continued at a high speed to return the clamp to initial position.

The mechanism for giving the gear 18 a single rotation during the sewing comprises a pinion 26 secured to the lower section of a vertical feed shaft 28. The feed shaft is driven from the sewing shaft 20 through a worm 30 secured to the sewing shaft, and 10 a worm wheel 32 secured to the upper section of the feed shaft. The gear 16 is driven through a single revolution during each cycle of the machine by a pinion 34 secured to or formed on a clutch sleeve 36 which is free to turn and slide on the feed shaft 28. The gear is driven at a high speed to operate the cutter and move the clamp into sewing position prior to the sewing, and to return the clamp to cutting position after the 20 sewing has been completed, through a high speed clutch 38, one member of which is formed on the upper end of the sleeve 36, and the other member of which is formed on a worm wheel 40 mounted to turn freely, 25 about the shaft 28 and driven through a worm 42 from a continuously rotating shaft 44. The gear 16 is driven at comparatively slow speed during the sewing of a button-hole through a feed clutch, one member of 30 which consists of a disk 46 formed on the lower end of the sleeve 36, and the other member of which consists of a spring-pressed pin 48 mounted in the pinion 26 and arranged to engage a shoulder or notch in the 35 disk.

In embodying the invention in its preferred form in a machine having the construction and mode of operation above described, the sleeve 36 is shifted to engage and disengage the clutches through which the feed cam gear 16 is actuated by a clutch lever 50, one end of which is connected to a ring 52 arranged between collars on the sleeve, and the other end of which is connected by a link 54 to a clutch shifting lever 56. A spring 58 is coiled about the pivot pin of the lever 50, and tends to shift the lever in a direction to engage the high speed clutch 38. The sleeve 36 is shifted to dis- 50 engage the high speed clutch in stopping the machine, by an arm 60 mounted on the clamp and arranged to act upon the end of the clutch shifter lever 56 as the clamp is moved into its initial position. The arm 60 also 55 operates to retain the clutch carrying sleeve 36 in position until the machine is to be started. The arm 60 is therefore retained in active position until the machine is to be started, and is then moved or allowed to 60 move into inactive position, and thus release the clutch shifting arm 56 and allow the high speed clutch to be engaged. In the construction shown, the clutch operating and retaining arm 60 is pivoted at its upper end 65 upon a bracket 62 formed on or secured to

the clamp carrier, and is retained in active position by a latch 64 formed on the rear end of a trip lever 66 which is pivoted to the bracket 62. The latch is provided with a notch adapted to engage a lug or shoulder 70 68 formed on the arm 60. A spring 70 is connected to the trip lever and arm 60, and tends to throw the arm into inactive position and to return the trip lever and latch to active position when the trip lever is released by the operator. After the high speed clutch has been engaged, and the machine thus started by operation of the trip lever, the shifting of the clutch sleeve 36 to successively engage and disengage the 80 high speed and feed clutches is controlled by a cam carried on the cam gear 16, and it is preferred to utilize for this purpose the same cam ledge which controls the throwing in and out of the clutch which drives the sewing shaft 20. In the construction shown this is accomplished by providing the clutch shifting lever 56 with a laterally projecting arm 72, the inner end of which extends downward into position to 90 ride on and off of the cam ledge 24.

When the machine is at rest the parts are in the position indicated in Fig. 2, and the clutch sleeve is held in position by the engagement of the arm 60 with the end of 95 the clutch shifting lever 56. At this time the lateral projection on the clutch shifting lever 56 registers with the space between the ends of the cam ledge 24, as indicated in Fig. 4. When the machine is to be started, the operator depresses the trip lever 66, thus releasing the arm 60 so that it may move into inactive position and release the clutch shifting lever 56. The clutch sleeve 36 is immediately shifted to engage the members 100 of the high speed clutch, and the cam gear 16 is driven at a high rate of speed. The high speed clutch continues to drive the gear until the inclined end of the cam ledge 24 engages the lever 56, and then the lever 105 is rocked by the cam ledge to shift the clutch sleeve 36 and thus disengage the high speed clutch and engage the feed clutch. At the same time the actuator bar 22 rides off the end of the cam ledge 24, thus throwing in the clutch which drives the sewing shaft 20. The gears 16 and 18 will now 110 be driven from the sewing clutch during the sewing and until the actuator bar 22 rides up the inclined end of the cam ledge 115 24 and disengages the sewing clutch. At this time the end of the clutch shifting lever 56 also rides off the other end of the cam ledge 24, so that the clutch sleeve 36 is again shifted to disengage the feed clutch and re- 120 engage the high speed clutch 38. While the gear 16 is being driven through the feed clutch, the clamp has been moved forward and then back to the position where the 125 sewing of the buttonhole began. During 130

the forward movement of the clamp the lower end of the arm 60 engages a fixed pin 74 and is swung back into active position, being retained in this position by the reengagement of the latch 64 with the lug 68. After the clutch shifting lever 56 has ridden off the end of the cam ledge, and the high speed clutch has been thus reengaged, the gear 16 will continue to be driven at 10 a high speed until the clamp reaches its initial position, when the end of the arm 60 will engage the end of the clutch shifting lever 56 and shift the clutch sleeve 36, thus disengaging the high speed clutch and stopping the machine.

While it is preferred to employ the specific construction and arrangement of parts shown and described in embodying the invention in the machine of the patent above referred to it will be understood that this construction and arrangement are not essential to the broader features of the invention, and may be varied and modified as found desirable or best suited to the construction 20 of the machine in which the invention is to be embodied.

Having explained the nature and object of the invention, and specifically described one form of mechanism in which it may be embodied, what is claimed is:—

1. A buttonhole sewing machine, having, in combination, stitch forming mechanism, a work clamp, a feed cam, mechanism for actuating the feed cam, means mounted on the work clamp for throwing the actuating mechanism out of action when the clamp is in its initial position, and a manually operated trip for rendering said means inactive in starting the machine.

2. A buttonhole sewing machine, having, in combination, stitch forming mechanism, a work clamp, a feed cam, mechanism for actuating the feed cam, a shifter for throwing the actuating mechanism into and out of action, an arm on the clamp for operating the shifter to throw out the actuating mechanism when the clamp comes into initial position, and a manually operated trip for retaining the arm in active position.

3. A buttonhole sewing machine, having, in combination, stitch forming mechanism, a work clamp, a feed cam, mechanism for actuating the feed cam, a shifter for throwing the actuating mechanism into and out of action, an arm on the clamp for operating the shifter to throw out the actuating mechanism when the clamp comes into initial position, a manually operated latch for retaining the arm in active position, and means for resetting the arm and latch during the travel of the clamp.

4. A buttonhole sewing machine, having, in combination, stitch forming mechanism, a work clamp, a feed cam, mechanism for actuating the feed cam, a shifter for throw-

ing the actuating mechanism into and out of action, an arm on the clamp for operating the shifter to throw out the actuating mechanism when the clamp comes into initial position, a manually operated latch for retaining the arm in active position, and a stationary pin for engaging the arm to reset the arm and latch during the travel of the clamp.

5. A buttonhole sewing machine, having, in combination, stitch forming mechanism, a work clamp, a feed cam, mechanism for actuating the feed cam means mounted on the work clamp for throwing the actuating mechanism out of action when the clamp is in initial position, a manually operated trip for rendering said means inactive in starting the machine, and a cam for controlling the actuating mechanism during the travel of the clamp.

6. A buttonhole sewing machine, having, in combination, stitch forming mechanism, actuating mechanism therefor, a work clamp, a feed cam for relatively moving the clamp and stitch forming mechanism, a cam connected with the feed cam for throwing said actuating mechanism into and out of action, and mechanism independently controlled by said latter cam for driving the feed cam at high and low speeds.

7. A buttonhole sewing machine, having, in combination, stitch forming mechanism, actuating mechanism therefor, a work clamp, a feed cam for relatively feeding the clamp and stitch forming mechanism, a clutch for driving the feed cam from said actuating mechanism, and a cam for throwing the actuating mechanism into and out of action and also engaging and disengaging the clutch.

8. A buttonhole sewing machine, having, in combination, stitch forming mechanism, a work clamp, a feed cam for the work clamp, high speed and feed drives for the cam, manually controlled means on the work clamp for rendering both drives inactive when the clamp is in initial position, and a cam for controlling the drives during the travel of the clamp.

9. A buttonhole sewing machine, having, in combination, stitch forming mechanism, driving mechanism therefor, a work clamp, a feed cam gear, a clutch for driving the cam gear from said driving mechanism during the sewing, a clutch for driving the cam gear before and after the sewing, manually controlled means on the work clamp for throwing the latter clutch into and out of action, and means for controlling the clutches at the beginning and end of the sewing.

10. A buttonhole sewing machine, having, in combination, stitch forming mechanism, driving mechanism therefor, a work clamp, a feed cam gear, a clutch for driving the

cam gear from said driving mechanism during the sewing, a clutch for driving the cam gear before and after the sewing, manually controlled means on the clamp for throwing 5 the latter clutch into and out of action, and a cam on the cam gear for shifting said clutches at the beginning and end of the sewing.

11. A buttonhole sewing machine, having, 10 in combination, stitch forming mechanism, driving mechanism therefor, a work clamp, a feed cam, a clutch for driving the feed cam from said driving mechanism during the sewing, a clutch for driving the feed cam 15 before and after the sewing, and a cam connected with the feed cam for controlling said driving mechanism and for shifting

said clutches at the beginning and end of the sewing.

12. A buttonhole sewing machine, having, 20 in combination, stitch forming mechanism, actuating mechanism therefor, a work clamp, a feed cam for relatively moving the stitch forming mechanism and work clamp, a cam ledge carried by the feed cam for controlling the throwing in and out of said actuating mechanism, and high speed and feed drives for the feed cam controlled by said cam ledge independently of the control of said actuating mechanism.

GEORGE S. HILL.
